UNITED STATES PATENT OFFICE.

EDGAR SECKLER GOSS AND SYLVESTER A. BARRICKMAN, OF FRANKLIN, PENNSYLVANIA.

PLUNGER AND VALVE FOR ARTESIAN OR WATER AND OIL WELLS.

1,192,619.

Specification of Letters Patent. Patented July 25, 1916.

Application filed August 19, 1915. Serial No. 46,385.

To all whom it may concern:

Be it known that we, EDGAR S. Goss and SYLVESTER A. BARRICKMAN, citizens of the United States, residing at Franklin, in the county of Venango and State of Pennsylvania, have invented a new and useful Plunger and Valve for Artesian or Water and Oil Wells; and we do hereby declare the following to be a full, clear, and exact 10 description of the invention, such as will enable others skilled in the art to which it appertains to make and use the same.

This invention relates to an improved plunger and valve for Artesian or water and oil wells, and an object of the invention is to provide a self-adjusting and cleaning device of this nature, which is simple, efficient and practical in construction.

Another object of the invention is to provide an improved check valve construction in the well, and one carried by the plunger, both of which can be unseated and held unseated, by virtue of lowering the plunger, in order to clear the well of sand and shale 25 or other refuse.

In practical fields the details of construction may necessitate alterations, falling within the scope of what is claimed.

The invention comprises further features 30 and combination of parts, as hereinafter set forth, shown in the drawings and claimed.

In the drawings:—Figure 1 is a view in side elevation showing the tubular unions of the wall of the well, of which there can be 35 any number, and in which the plunger and valves are designed to be arranged. Fig. 2 is a sectional view showing the plunger and the valves in positions under normal conditions. Fig. 3 is a sectional view showing 40 the plunger and valves in positions when the well is being cleared of the refuse. Fig. 4 is a transverse sectional view on line 4—4 of Fig. 2. Fig. 5 is a transverse sectional view on line 5—5 of Fig. 2. Fig. 6 is a 45 transverse sectional view on line 6—6 of Fig. 2. Fig. 7 is a transverse sectional view on line 7—7 of Fig. 2. Fig. 8 is a transverse sectional view on line 8—8 of Fig. 2. Fig. 9 is a transverse sectional view on line 9—9 50 of Fig. 2. Fig. 10 is a detail perspective view of a member adapted to be carried by the plunger, for holding the valve in a cage of the plunger unseated, when cleaning the well of the refuse and the like.

55 Referring to the drawings, 1 and 2 design-

uate the two unions or sections of the wall of the well threaded together as at 3, and the opposite ends of which are provided with threads 4 and 5, whereby other sections may be connected, if it is so desired. It is to be 60 noted that the section 2 threads upon the interior of the section 1, so that its lower end will form an abutment 6, to hold the casing 7 in place, against the action of the spring 8, which is interposed between the 65 disk valve seat 9 and the annular flange 10 of said casing 7. The disk valve seat 9 rests upon the shoulder 11 upon the interior of the section 1 adjacent its lower end, and is provided with a series of perforations or 70 openings 12, through which the fluid passes into the casing 7. Resting upon the disk valve seat is a piston lift or plunger 13. The lower portion of this lift is in the form of a body, similar to that shown in Fig. 10, and 75 this body is provided with a plurality of wings 14 extending radially, and of the shape shown in side elevation, and is shrunk or threaded or otherwise secured upon the lower end of the lift, stem, or plunger. The 80 upper end of the lift or stem terminates in a head 15, of a construction similar to the body, but smaller, and of a straight contour in side elevation and having wings 16. This head extends into but is spaced apart from 85 the interior surface of the sleeve 17, so that the fluid and refuse will pass through said sleeve. The sleeve 17 at its lower end has exterior threads 18 to engage the interior threads of a cage or skeleton sleeve 19, 90 through the lower end of which the cylindrical portion 20 of the stem or lift (which cylindrical portion 20 is of uniform diameter in cross section throughout its length) telescopes. Interposed between the cage or 95 skeleton sleeve and the body and surrounding the cylindrical portion 20 is a coil spring 21, for holding the cage or skeleton sleeve 19 in the position shown in Fig. 2. The upper end of the sleeve 17 has exterior 100 threads 22 engaging the interior thread of the valve cage 23, thereby supporting the cage upon the sleeve. Interposed between the valve cage 23 and the cage or skeleton sleeve 19, and surrounding the sleeve 17 is a plurality of packing members or washers or cups 24 engaging the interior surface of the casing 7, thereby preventing the fluid from passing between the sleeve 17 105 and the inner wall or surface of the casing 110

7. A gravity actuated ball valve 25 is arranged upon the interior of the cage 23 (which is provided with an opening 26 at its upper end and openings 27 in its sides) and is designed to coöperate with the valve seat 28 of the upper end of the sleeve 17. The plunger 29 has a valve cage 30 threaded at 31 to its lower end having openings 32 in its side wall, and includes a gravity actuated ball valve 33, which coöperates with the valve seat 34 of the sleeve 35, which is threaded at 36 into the cage 30.

A cage or skeleton sleeve 37 is threaded to the lower end of the sleeve 35, and between the cage 37 and the cage 30 are suitable packing members or cups or washers 38, similar to the cups or washers or packing members 24, and engaging the interior cylindrical wall of the section or union 2 of the wall of the well, thereby constituting a suction piston. Telescoping the cage or skeleton sleeve 37 is a valve lift, or stem or plunger 39 similar to the lift or stem 13, there being a spring 20^a similar to the spring 21, for holding the lift 39 in the position shown in Fig. 2. In Fig. 2 it will be observed that the springs 21 and 20^a are distended, the lower parts of said springs are extended into the counter-bores 40 of said bodies 30 of the lifts, and their upper end portions are attached at 42 to the cages 19 and 37.

In the operation the plunger upon its upward movement owing to its piston 38 contacting with the interior wall of the section 2 of the wall of the well, a suction is created below the piston or packing 38, thereby lifting the ball valve 25 against gravity, thereby sucking the fluid through the casing 7 upwardly through the sleeve 17, and above the ball valve 25. Upon the downward movement of the plunger rod or valve stem 29, the ball valve 25 seats not only by gravitation, but also owing to the pressure of the fluid (which then passes through the cage 37, the sleeve 35 and lifts the valve 33 and passes above the same thereabove). This operation is continuous, when pumping the fluid.

50 When it is desired to clear the well of the sand, shale or other refuse, the plunger rod or valve stem 29 is lowered until the body of the lifting member 39 contacts with the cage 23. The plunger rod or valve stem is then further lowered, and owing to the cage 30 (to which the cage 37 is connected by means of the sleeves 35) being connected to said rod or valve stem and moving therewith, the valve lifting member 39 will move upwardly through the cage 37 and sleeve 35, thereby lifting or unseating the ball valve 33, and owing to the cage 23 (to which the cage 19 is connected by the sleeve 17) being moved downwardly by pressure of the lifting member 39 thereon, the lifting mem-

ber 13 will lift or unseat the ball valve 25, then owing to both ball valves being lifted or unseated, the sand, shale or other refuse will have substantially a clear passage out through the valve mechanisms. If desired, another valve mechanism may be arranged above the uppermost valve mechanism shown, in which case the plunger rod or valve stem 29 may be connected to it, instead of to the cage 30, in which case the operation of the mechanism is substantially the same as heretofore set forth.

The invention having been set forth, what is claimed as new and useful is:

1. In a device for elevating liquids, a tubular casing of substantially one uniform diameter having a disk valve seat, an inner valve casing movable within the first casing and being yieldably mounted on said valve seat, a valve mechanism in said valve casing and including a ball valve and seat therefor, and a plunger rod having a piston and a ball valve mechanism to coöperate with the first valve mechanism for lifting the fluid.

2. In a device for elevating liquids, a tubular casing of substantially one uniform diameter having a disk valve seat, an inner valve casing movable within the first casing and being yieldably mounted on said valve seat, a valve mechanism in said valve casing and including a ball valve and seat therefor, and a plunger rod having a piston and a ball valve mechanism to coöperate with the first valve mechanism for lifting the fluid, said first valve mechanism including a member adapted to raise its valve when the mechanism is depressed, the second valve mechanism including a member adapted to raise its valve, and which second member, when the plunger rod is moved downwardly, contacts with and moves the first valve mechanism causing the first member to raise its valve, and while the rod moves the second valve mechanism downwardly causes the second member to raise its valve, thereby permitting a free passage, whereby the refuse may pass out.

3. In a device for elevating liquids, a tubular casing of substantially one uniform diameter having a disk valve seat, an inner valve casing movable within the first casing and being yieldably mounted on said valve seat, a valve mechanism in said valve casing and including a ball valve and seat therefor, and a plunger rod having a piston and a ball valve mechanism to coöperate with the first valve mechanism for lifting the fluid, said first valve mechanism including a member adapted to raise its valve when the mechanism is depressed, the second valve mechanism including a member adapted to raise its valve, and which second member, when the plunger rod is moved downwardly, contacts with and moves the first valve mechanism causing the first member to raise its valve

valve, and while the rod moves the second valve mechanism downwardly causes the second member to raise its valve, thereby permitting a free passage, whereby the refuse may pass out, and means for restoring the valve mechanisms and their ball valve to their seats.

In testimony whereof we have signed our

names to this specification in the presence of two subscribing witnesses.
